CLEAT CLEANER

Olaf Homme, Granite Falls, Minn.

Application August 29, 1951, Serial No. 244,202

3 Claims. (Cl. 15—36)

This invention relates to apparatus for the cleaning of cleats which are attached to the soles of athletic shoes and is especially adapted to be used during the progress of athletic games to remove mud and other foreign material which may cling to and between the cleats of such shoes worn by the players.

It has long been the practice of players in athletic competition to wear footwear which is especially adapted for the particular game which they are playing. Thus, baseball players wear a moderately soft shoe which contains metal cleats of a more or less standard arrangement which are adapted to pierce the earth to a proper degree to prevent slipping of the player's foot while he is running or jumping and still will offer but minimum interference with his other activities such as batting, sliding and throwing. Further, the cleats are designed so as to be effective with the least danger to other players and the least likelihood of catching in the player's clothes. Football shoes require a larger and more sturdy construction with a broader based cleat having a slightly greater height. Likewise, track shoes have longer and sharper cleats. Each of these specially adapted shoes have the common difficulty of collecting mud and foreign material which reduces the effectiveness of the gripping action of the cleats and becomes a continual annoyance to the player. This is especially true where games are played on damp ground. Since the advent of night football and baseball, the players find that dew on the grassy portion of the field will cling to the soles of their shoes and will pick up dust and other foreign material which accumulates between the cleats of their shoes and then becomes caked. It has been the practice of athletic contestants experiencing this difficulty to use some extraneous means of removing the caked mud or foreign material. For example, baseball players may often been seen to strike the side of their shoes with a bat to dislodge some of the material. If it is badly caked they may dig at it with their fingers or in some instances they may be required to take time out to use a pointed stick, knife or any other makeshift tool which they may find in the vicinity. In any event, the cleaning job is unsatisfactory and further, the knocking or rapping of the shoe by the baseball player's bat will soon cause irreparable damage to the shoe. Football players likewise must remove the caked mud and foreign material in order to utilize the full benefit of the gripping action of their cleats. Here again there is no satisfactory method of removing such caked material and makeshift tools or the player's fingers are usually employed to remove at least a portion of the material.

It is therefore a principal object of this invention to provide for a cleat cleaning apparatus which will quickly and efficiently remove substantially all the caked mud or foreign material which may form on the sole and between the cleats of an athletic contestant's shoe at intervals as required during the course of the game which he is playing and which does not necessitate the use of the player's hands or removal of the shoe from the player's foot.

It is another object of this invention to provide a cleat

2

cleaning apparatus which will quickly and positively remove all the caked material from between the cleats of the athletic contestant's shoes by the simple expedient of the player placing his foot with the cleats of his shoes between the guides which are in predetermined spaced relation to one another and pulling his foot downwardly in a natural movement such as he may employ to wipe or scrape the soles of ordinary shoes which do not bear cleats.

It is another object of the invention to provide guide means for the cleat cleaner which will position the foot in a positive manner and prevent the accidental twisting or turning of the player's foot while the shoe is being moved in predetermined travel across the cleat cleaning device which is necessarily powered to a degree creating a force against which the player cannot voluntarily hold his foot in the desired relationship.

It is a still further object of this invention to provide for a cleat cleaning device which has moving brush means for removing the caked mud and foreign material from between the cleats of the player's shoes and which has a novel and simple means for adjusting the effective length of the bristles available for cleaning in accordance with the type of cleated shoe which is to be cleaned.

These and other objects and advantages of my invention will more fully appear from the following description made in connection with the accompanying drawings wherein like reference characters refer to similar parts throughout the several views and in which:

30. Fig. 1 is a perspective view of my invention.

Fig. 2 is a side elevation of my cleat cleaning device showing in dotted line representation an athletic shoe and an adjusted new position of the motor with attached brush.

Fig. 3 shows a segmented section of the athletic shoe and brush and guide elements taken on the line 3—3 of Fig. 2.

Referring to the drawing my invention includes a fixed structure having a base 10 extending substantially under the entire device. Along one edge of the base 10 is fastened a housing H having end walls 11 and 12 and side walls 13 and 14. The end walls 11 and 12 contain arched openings 15 adjacent the base 10 which serve as openings for cleaning out any accumulated dirt and foreign material which may gather on the inside of the housing H defined by the walls above described. The side walls 13 and 14 form at their top edges a plane angular to the surface of base 10. Guard members 16 and 17 extend across the beveled edges of walls 13 and 14 to prevent mud and foreign material from being uncontrollably ejected from the device in an undesirable manner.

50. Also secured to base 10 are mounting brackets 18 and 19. The brackets 18 and 19 are parallel to the side wall 13 and are situated in spaced relation for the mounting of a motor unit 20 in the preferred form of my invention. It is to be understood, of course, that where independent power means is supplied a journal assembly may be substituted for the motor 20 and likewise be adjustably mounted upon the brackets 18 and 19. Stud bolts 21 are affixed to the brackets 18 and 19 so as to be positioned in the slots 22 of the base 23. Wing nuts 24 may be threaded upon the studs 21 for adjustably securing the journal assembly or motor 20 upon the brackets 18 and 19.

55. The journalled shaft or motor shaft 25 extends through a slotted opening 26 formed in the side 13 to allow for lateral adjustment of the motor together with its shaft 25 upon the mounting brackets 18 and 19. Fixed to the shaft 25 and rotating therewith is a brush element 27. The bristles 28 of the brush 27 extend radially outward from the shaft 25 and are constructed from a stiff and rugged substance such as steel wire. The bristles 28 are formed in a circular brush which is centrally located between the side walls 13 and 14. Fixed to the top of the

60. 65. 70. 75. 80. 85. 90. 95.

housing element H and angulated from one side to the other is a guide, the guide having a pair of bars 29 and a slot or guideway extending longitudinally thereof and continuing in unobstructed manner through the bottom edge of the guide. The guide has a flat and plane upper surface at each of the bars 29 and also has vertical cleat contacting surfaces in opposed relation at the inside edges of bars 29, the vertical cleat contact surfaces defining said guideway or slot. The guards 16 and 17 close a portion of the guideway from communication with the interior of housing H but define a rectangular opening or aperture through which the circular brush bristles 28 may extend. The entire unit may be conveniently portable and a handle 30 affixed to the base 10 may be employed to carry the unit from one location to another.

In the operation of my apparatus the electrical connection of the motor 20 is placed in a suitable electrical outlet preferably associated with the dugout or reserved player section of an athletic field, one for each of the competing teams. The motor 20 together with its brush element 27 is adjusted horizontally on brackets 18 and 19 so that the bristles 28 project through the guide space between the guide bars 29 for a distance appropriate for the type of athletic shoe to be cleaned. The bristles need not bear heavily against the sole of the shoe, it being merely necessary that they wipe the ends and sides of the cleats 31 of the shoe 32 as shown in Figs. 2 and 3. When a player is troubled with an accumulation of mud or foreign material between the cleats of his shoes, he stands forwardly of the surface of the inclined top of housing element H and places each foot consecutively upon and near the top of guide bars 29 with the cleats 31 positioned therebetween. He then brings his foot slowly downward so as to maintain the cleats within the guide space and bearing simultaneously upon the stiff bristles 28 of the brush element 27. The direction of rotation of the brush element 27 is such that the bristles in contact with the cleats 31 are moving forwardly and upwardly to oppose the downward movement of the foot. The player in overcoming the action of the stiff bristles brings his foot firmly back down to the ground in front of the apparatus in a natural, wiping action. The spaced relation of the guide bars 29 and their natural angle make the entire cleaning operation an extremely quick and simple one. Accumulations of mud and foreign material will lie upon the base 10 within the housing H and will fall through either of the arched openings 15 when the apparatus is tilted forwardly or backwardly at the end of each game. If so desired my invention contemplates the use of clean-out drawers at either end of the housing H. Where the nature of the athletic footwear requires a wider space between the guide bars 29 the distance therebetween may be altered so as to allow for the entry therein of the cleats while still maintaining contact by the outer edge of the sole with the guide bar 29.

It will thus be seen that I have constructed a novel and simple arrangement of elements whereby the athletic shoe of a contestant may be cleaned while on his foot with a minimum of effort on his part and without requiring the use of fingers, sticks or other extraneous makeshift articles. The length of time required for the purpose of cleaning such shoes is thereby minimized since the players can ordinarily clean their cleats on my device during natural intervals occurring during the game without calling special time-out periods for such purposes.

It will, of course, be understood that various changes may be made in the form, details, arrangement and proportions of the parts without departing from the scope of my invention.

What I claim is:

1. Apparatus for cleaning foreign substances such as caked mud from the cleats of an athletic shoe having cleated soles, said apparatus comprising, a fixed structure in the nature of a housing, a guide rigidly secured to the top of said housing and angulated with respect to the

horizontal from one side to the other thereof, said guide having a flat and plane upper surface for at least a substantial part of its length and a straight and unobstructed vertical cleat contacting surface extending for a substantial portion of the length of said guide, a stiff-bristled brush element mounted for movement adjacent the vertical surface of said guide, the bristles of said brush terminating outwardly at least as far as the plane of said upper surface during movement of the brush, and power means for driving said brush whereby said cleats will be cleaned when the cleated shoe is pulled downwardly with the sole thereof in firm contact with the said upper surface and the cleats thereof in guided contact with said vertical surface, and said shoe being movable in such guided contact completely through the lower end of said angulated guide.

2. Apparatus for cleaning foreign substances such as caked mud from the cleats of an athletic shoe having cleated soles, said apparatus comprising, a fixed structure in the nature of a housing, a guide rigidly secured to the top of said housing and angulated with respect to the horizontal from one side to the other thereof, said guide having a flat and plane upper surface for at least a substantial part of its length and a straight and unobstructed guide slot having vertical cleat contacting surface extending all the way to the lower end of said angulated guide, a guard underlying the guide slot and having an aperture formed therethrough, a circular stiff-bristled brush element journaled for rotational movement adjacent and relative to the vertical surface of said guide, the bristles of said brush extending through the aperture and terminating outwardly at least as far as the plane of said upper surface during rotation of the brush, and power means for driving said brush whereby said cleats will be cleaned when the cleated shoe is pulled downwardly with the sole thereof in firm contact with said upper surface and the cleats thereof in guided contact with said vertical surface and said shoe being movable in such guided contact completely through the lower end of said angulated guide.

3. Apparatus for cleaning foreign substances such as caked mud from the cleats of an athletic shoe having cleated soles, said apparatus comprising a fixed structure in the nature of a housing, a base secured to said housing, spaced parallel guide bars rigidly secured to the top of said housing and presenting an upwardly angulated plane for positioning a marginal area of said shoe sole thereagainst with the cleats thereof positioned between the guide bars for longitudinal sliding travel, a motor mounted on said base and adjustable to one of a multiplicity of rigid positions in the same longitudinal direction as that of the spaced guide bars, and having a rotatable power shaft substantially normal to the longitudinal direction of said spaced parallel guide bars and positioned thereunder, a stiff-bristled rotary brush axially secured to said shaft, the circumference thereof lying between said guide bars, and adjustment means for effecting said rigid adjustment of the motor and rotary brush with respect to the base, whereby the effective circumference of said brush bristles will be advanced and retracted to rigid fixed position with the brush bristles terminating at least in the plane of said upwardly angled plane.
